UNITED STATES PATENT OFFICE.

ROBERT A. RUSSELL, OF RIDGEWOOD, NEW JERSEY, ASSIGNOR TO PARAGON CAN & CAP COMPANY, INC., OF PATERSON, NEW JERSEY, A CORPORATION OF NEW YORK.

RECEPTACLE CLOSURE.

Application filed March 26, 1923. Serial No. 627,710.

To all whom it may concern:

Be it known that I, ROBERT A. RUSSELL, a citizen of the United States, and resident of Ridgewood, in the county of Bergen and State of New Jersey, have invented a new and useful Improvement in Receptacle Closures, of which the following is a specification.

This invention relates to a receptacle closure and, more particularly, to a so called screw cap for bottles and jars, such for instance, as a catsup bottle.

An object of the invention is to provide such an article which is designed to engage threads formed on the inside of the neck of the receptacle, and which includes effective means for establishing a substantially perfect sealing engagement between the closure and the receptacle.

Another object consists in providing such a device which may be cheaply and expeditiously manufactured and which will be sightly in appearance.

A further object consists in providing certain improvements in the form, construction and arrangement of the several parts whereby the above named and other objects may be effectively attained.

Receptacle closures which are provided with threads designed to mate with threads formed on the inside of the neck or mouth of the receptacle have usually been provided with rings or washers of cork, rubber composition or other yielding material, such rings or washers being arranged to lie between the top edge of the receptacle neck or mouth and a shoulder or flange formed on the closure, so that the rings or washers would be compressed upon the receptacle in an axial direction, when the cap or closure was in position thereon. This construction has not proved entirely satisfactory from the point of view of effecting a complete seal, largely because there was nothing comparable to a wedging action in the application of the closure to the receptacle, and also because of the difficulty of acting upon the discs or washers with sufficient force to thoroughly accomplish the desired result.

Furthermore, it frequently happens that glass receptacles, such as catsup bottles, have minute cracks or fissures existing at the lip

or extreme edge of the neck of the receptacle, as a result of the process of manufacturing the receptacle. These cracks or fissures commonly extend inwardly about one-eighth of an inch, considered in the direction of the height of the receptacle, and permit a certain amount of leakage through the part of the receptacle where they occur. It will be clear that a ring or washer which presses only upon the outer edge of the receptacle will not serve to close these cracks or fissures and will not, therefore, accomplish an effective seal.

With these well known disadvantages in mind, I have devised the present invention, a practical embodiment of which is represented in the accompanying drawings, in which—

Fig. 1 represents a detail elevation, partly in section, showing my improved closure applied to the neck of a bottle.

Fig. 2 represents a detail elevation, partly in section, showing the closure just before it is applied to the receptacle.

Fig. 3 represents a detail section, through a modified form of the invention, in which it is shown applied to a hot water bottle.

Referring to Figs. 1 and 2, the closure is preferably composed of sheet metal, such as sheet iron which has been coated with tin and lacquered, and consists of an upper member 1 and a lower member 2. The upper member is formed substantially in the shape of a flat cylinder and can readily be drawn from a blank of sheet metal by a die operation, in a manner well understood in the art.

The lower member 2 of the closure includes a flange 3 which is interlocked with the upper member 1 by means of a folded seam 4. This seam is of conventional character and may be formed by a dieing operation which is familiar to all those skilled in this industry.

The member 2 also includes a portion which is denoted by 5 and is substantially cylindrical in form. This portion 5 intervenes between the flange 3 and a threaded portion 6 at the lower part of the member 2.

The flange 3 has a bead 7 formed thereon so as to project downwardly toward the threaded portion of the member 2.

In manufacturing the member 2, it may

- be drawn by a suitable die operation, with the flange 3 projecting laterally and with the portions 5 and 6 substantially cylindrical in form. This same operation may im-
5 press the bead 7 in the flange 3. After the member 2 has been thus formed, the portion 6 is suitably threaded by passing it between the well known threading rollers, and the flange 3 is bent into interlocking engage-
10 ment with the member 1, as previously de-
scribed.
- The seam 4 not only serves to firmly unite the members 1 and 2, but it constitutes a beading which improves the appearance of the closure and strengthens or reinforces the flange 3.
- A ring or washer 8, of suitable compressible material, such as rubber compound, is fitted around the cylindrical portion 5 of
20 the member 2 so as to lie adjacent the under side of the flange 3 and bead 7. This washer will normally be held in place by its frictional grip upon the portion 5.
- The outside diameter of this portion 5 is
25 made less than the inside diameter of the neck of the receptacle 9 at its mouth, and the outside diameter of the washer 8 is made greater than the diameter of the said portion of the receptacle, so that the said
30 washer may be forced into position on top of and also within the mouth of the receptacle. The upper inner edge of the receptacle is formed with a shoulder or seat 10, and it will be observed that this shoulder,
35 which is annular in form, has a radius slightly greater than the radius of the bead 7. Immediately below the seat 10, the said inner edge or mouth of the receptacle tapers inwardly toward its threaded portion,
40 as indicated at 11.
- The result of the foregoing arrangement is that, when the closure is applied to the receptacle by screwing it thereon, the washer 8 enters for some distance inside the mouth
45 of the receptacle so as to be clamped between the said tapered portion 11 of the receptacle and the cylindrical portion 5 of the member 2 of the closure. Another part of the washer 8 is firmly clamped between the bead 7 and shoulder 10, while the outer part
50 of the washer rests upon the top face of the neck of the receptacle and is clamped thereupon by the flange 3. This condition of the washer is clearly shown in Fig. 1.
- 55 Thus the washer 8 not only bears upon the portions of the receptacle just mentioned in order effectively to seal any cracks or fissures and to cover any irregularities in the material of which the receptacle is com-
60 posed, but the said washer is forced into place by a wedging action similar to that which occurs when an ordinary cork is forced into the neck of a bottle, and it is also clamped between two projections, to
65 wit: the bead 7 and shoulder 10, at an in-
termediate point, so that a most complete and perfect sealing engagement is established.
- For the purpose of securing an additional sealing contact and thereby further insur-
70 ing an air-tight engagement between the closure and receptacle, I provide a second inner annular shoulder 12 in the neck of the receptacle, which shoulder is adapted for engagement by the bottom of the mem-
75 ber 2 of the closure, with the intermedia-
tion of a sealing disc or wafer 13. This disc 13 may be composed of any suitable material, such as wax paper, and it is shown in the present instance as being crimped up
80 around the periphery of the member 2 of the closure for the purpose of holding it in place upon the latter. It may be desirable also to apply adhesive between the disc 13 and member 2 as an additional means of
85 uniting these two parts, or the adhesive might be employed without crimping the edge of the disc around the periphery of the member 2. This disc may also serve to protect the closure from the action of the
90 contents of the receptacle.
- It will be seen that, as the closure is screwed down into the sealing engagement above described, the bottom of the member
95 2 will firmly compress the disc 13 upon the shoulder 12, at the same time that the flange 3 and bead 7 are exerting pressure upon the washer 8, so that a very tight engagement is effected at the shoulder 12 as well as at the other points described, and there is set
100 up a sealing contact between the closure and receptacle which has three distinct points, one on top of the receptacle, another just within the mouth of the receptacle, and the third at the shoulder 12.
- 105 For convenience in manual operation of the closure, it is preferably provided with a knurling, which can be done at the same time that the portion 6 is being threaded, as is well known by operatives in this industry.
- 110 Referring to the modified form shown in Fig. 3, the neck of a hot water bottle is denoted by 14, and it is provided with the usual screw threaded member 15 which is composed of sheet metal and preferably secured in the neck 14 by a vulcanizing process well understood in the art. The bottom of this screw threaded member 15 is open and provided with a peripheral flange 16 which projects laterally inwardly from the wall of the neck 14; while the top of the said member 15 has a folded flange 17 that projects laterally outwardly and rests upon a shoulder in the neck 14.
- 115 The closure consists of an upper member 18 and a lower member 19 that are united by a folded seam, which seam itself constitutes an outwardly projecting lateral flange
120 20 on the closure, and the lower part of which is provided with a bead 21.

In manufacturing the member 19, it may be drawn by a suitable die operation with the flange projecting straight out laterally. In this same operation, the bead 21 may be formed. After the member 19 has been thus formed, it is suitably threaded by passing it between the well known threading rollers. The member 18 is produced by stamping it from sheet metal, and it may then have a suitable handle 22 riveted to it for the manual operation of the closure. The member 18 is of somewhat greater diameter than the threaded portion of the member 19, so that the said members 18 and 19 can then be united by placing the member 18 upon the outwardly projecting flange of the member 19 and folding the flange back upon the top of the member 18. This also is a well understood die operation.

20 The member 19 has a cylindrical portion 23 intervening between the flange 20 and its threaded portion; and a ring or washer 24, of suitable compressible material, such as rubber compound, is fitted around the cylindrical portion 23 so as to lie adjacent the under side of the flange 20 and bead 21.

25 A disc or wafer 25 composed of suitable material, such as wax paper, is fitted to the bottom of the member 19, and crimped around the periphery thereof for the purpose of holding the same in position. An adhesive may be used for this purpose, either with or without the crimping of the disc 25 around the periphery of the member 19, as mentioned in connection with the preferred form.

30 The operation of this embodiment of the invention is substantially the same as that of the preferred form, since it will be seen that, as the closure is screwed into the neck 14 of the water bottle, the washer 24 will be pressed down upon the top of the flange 17 by the flange 20, and the said washer will also be forced in between the inner end of the flange 17 and the threaded portion of the member 19 by the bead 21; while the bottom of the member 19 will simultaneously compress the disc 25 upon the flange 16; thus forming a triple seal similar to that set forth in describing the preferred form shown in Figs. 1 and 2.

35 It will be clear that the members 1 and 2 of the preferred form, and the members 18 and 19 of the modified form may be made in ways other than those hereinabove described, and that it may be desirable to subject the closures to an additional coating or recoating of some non-corrosive material, such as tin or lacquer, after they have been formed; and I desire it to be understood that various changes may be resorted to in the material, form, construction, arrangement and method of forming the various parts without departing from the spirit and scope of my invention; and that I do not in-

tend to be limited to the details herein shown and described, except as they may be included in the claims.

What I claim is:

1. In combination, a receptacle having interior closure engaging means, a shoulder located below said means, a shoulder located above said means, and a surface surrounding and above said last named shoulder, together with a sheet metal closure comprising an upper member, a lower member provided with a laterally extending flange, a seam at the perimeter of said flange uniting said members, said lower member being adapted to cooperate with the shoulder located below the closure engaging means, and said flange being adapted to cooperate with the shoulder located above the closure engaging means and with the surface surrounding said last named shoulder. 70

2. In combination, a receptacle having interior closure engaging means, a shoulder located below said means, a shoulder located above said means, and a surface surrounding and above said last named shoulder, together with a sheet metal closure comprising, an upper member, a lower member provided with a laterally extending flange, a seam at the perimeter of said flange uniting said members, a downwardly projecting bead on said flange, said lower member being adapted to cooperate with the shoulder located below the closure engaging means, said bead being adapted to cooperate with the shoulder located above said closure engaging means, and said flange being adapted to cooperate with the surface surrounding said last named shoulder. 90

3. In combination, a receptacle having interior closure engaging means, a shoulder located below said means, a shoulder located above said means, and a surface surrounding and above said last named shoulder, said shoulders being substantially parallel with each other and the last named shoulder being greater in diameter than the other, together with a sheet metal closure comprising, an upper member, a lower member provided with a laterally extending flange, a seam at the perimeter of said flange uniting said members, said lower member being adapted to cooperate with the shoulder located below the closure engaging means, and said flange being adapted to cooperate with the shoulder located above the closure engaging means and with the surface surrounding said last named shoulder. 105

4. In combination, a receptacle having interior closure engaging means, a shoulder located below said means, a shoulder located above said means, and a surface surrounding and above said last named shoulder, said shoulders being substantially parallel with each other and the last named shoulder being greater in diameter than the other, to

gether with a sheet metal closure comprising, an upper member, a lower member provided with a laterally extending flange, a seam at the perimeter of said flange uniting said members, a downwardly projecting bead on said flange, said lower member being adapted to cooperate with the shoulder located below the closure engaging means, said bead being adapted to cooperate with the shoulder located above said closure engaging means, and said flange being adapted to cooperate with the surface surrounding said last named shoulder.

5. In combination, a receptacle having inferior closure engaging means, a shoulder located below said means, a shoulder located above said means, and a surface surrounding and above said last named shoulder, said shoulders and said surface being substantially parallel with each other, the last named shoulder being greater in diameter than the other shoulder, and the surface being greater in diameter than either shoulder, together with a sheet metal closure comprising, an upper member, a lower member provided with a laterally extending flange, a seam at the perimeter of said flange uniting said members, said lower member being adapted to cooperate with the shoulder located below the closure engaging means, and said flange being adapted to cooperate with the surface surrounding said last named shoulder.

operate with the shoulder located above the closure engaging means and with the surface surrounding said last named shoulder.

6. In combination, a receptacle having inferior closure engaging means, a shoulder located below said means, a shoulder located above said means, and a surface surrounding and above said last named shoulder, said shoulders and said surface being substantially parallel with each other, the last named shoulder being greater in diameter than the other shoulder and the surface being greater in diameter than either shoulder, together with a sheet metal closure comprising, an upper member, a lower member provided with a laterally extending flange, a seam at the perimeter of said flange uniting said members, a downwardly projecting bead on said flange, said lower member being adapted to cooperate with the shoulder located below the closure engaging means, said bead being adapted to cooperate with the shoulder located above said closure engaging means, and said flange being adapted to cooperate with the surface surrounding said last named shoulder.

In testimony, that I claim the foregoing as my invention, I have signed my name this 23rd day of March 1923.

ROBERT A. RUSSELL.
